CHARLES D. YOUNG, OF WILMINGTON, DELAWARE.

BRAKE-RELEASE SPRING.

1,322,215.

Specification of Letters Patent.

Patented Nov. 18, 1919.

Application filed August 27, 1917. Serial No. 188,356.

To all whom it may concern:

Be it known that I, CHARLES D. YOUNG, a citizen of the United States, residing at Wilmington, in the county of New Castle 5 and State of Delaware, have invented certain new and useful Improvements in Brake-Release Springs, of which the following is a specification.

This invention relates in general to brake- 10 release means and particularly to a release means for locomotive, car, or tender brakes, and it has for its object the provision of a spring for the purpose specified which will be effective in operation, simple in construc- 15 tion, and adapted to be most easily and readily applied, and one which requires no special bolts or other fastening means to hold it in its place. A clear understanding of this invention can best be obtained by 20 referring to the accompanying drawings forming a part of this application, which illustrate it as applied to a railway car truck.

Figure 1 of the drawings is a partial per- 25 spective view of a car truck showing my release-spring applied thereto; and Figs. 2, 3, and 4 are various views of the spring by itself.

Referring to Fig. 1 the car wheel is 30 indicated by the numeral 1, the brake-head by 2, the brake-shoe by 3, the brake-beam by 4, the hanger by 5, the bolster by 6, the bolster spring by 7, and the truck frame by 8. The hanger is pivoted to the hanger 35 bracket 9 by means of the hanger bolt 10.

The release spring 11 is, as shown, of a general U-shape inverted with off-set eye portions 12, one in each arm of the U, which are so arranged that the hanger bolt 10 40 projects through the said eye-portions thereby positioning and fastening the spring. This fastening means is the only one provided, no special or extra screws, bolts or parts of any kind being necessary.

45 The portion of the spring projecting above the hanger-bolt bears against the hanger-bracket and each of the two arms portions projecting below the bolt is provided with a hook portion 13 adapted to engage the 50 arms of the brake hanger, all as clearly shown in the drawings, from which it will

be seen that movement of the brake-beam toward the wheels, which occurs when braking pressure is applied, puts the spring under tension. Upon release of the brake the 55 springs will immediately throw the brake hangers away from the wheel thereby taking the brake shoes out of contact therewith. It is, of course, understood that there are two such springs, one at each end of the 60 brake beam.

It will be seen that while I have shown as a preferred form the use of a wire of round cross-section and have supported my spring from the bolt of the hanger, a like 65 construction could be employed with the use of flat spring supported from the lug itself and not necessarily embracing the bolt but passing through supporting slots on either 70 the lug or the lug and bolt.

I claim:

1. The combination with a hanger bracket, a brake beam hanger and the hanger bolt, of a spring bearing against said bracket and said hanger and supported from said 75 bolt, said spring normally tending to hold the hanger in release position.

2. The combination with a hanger bracket, a brake beam hanger and the hanger bolt, of a U-shaped spring each arm of which 80 engages an arm of the hanger and the base of which engages the hanger bracket, there being an off-set eye portion in each arm intermediate the ends adapted to be engaged by the hanger bolt.

3. The combination with a hanger bracket, a brake beam hanger and the hanger bolt, of a spring supported intermediate its ends and bearing against said bracket and said hanger, said spring normally tending to 90 hold the hanger in release position.

4. The combination with a hanger bracket, a brake beam hanger having two arms, and a hanger bolt, of a U-shaped spring the top of which engages the bracket and which 95 has each of its free ends shaped to embrace an arm of the hanger, said spring having an eye portion intermediate its ends adapted to be engaged by the hanger bolt.

In testimony whereof I have hereunto 100 signed my name.

CHARLES D. YOUNG.
